US0D1086208S

(12) **United States Design Patent** (10) **Patent No.:** **US D1,086,208 S**
(45) **Date of Patent:** **** Jul. 29, 2025**

(54) **COOLANT FILLER PORT FOR A VEHICLE**

(71) Applicant: **Jenvan Innovations Inc.**, Concord (CA)

(72) Inventor: **John Veloso**, Maple (CA)

(73) Assignee: **JENVAN INNOVATIONS INC.**, Concord (CA)

(**) Term: **15 Years**

(21) Appl. No.: **29/899,340**

(22) Filed: **Aug. 8, 2023**

(51) **LOC (15) Cl.** **15-01**

(52) **U.S. Cl.**

USPC **D15/5**

(58) **Field of Classification Search**

USPC D15/5; D12/166, 172, 177, 197, 345;
D23/206, 261, 263, 387, 393

CPC F01P 11/0276; F01P 11/029; F01P 11/04;
F01M 11/0408; B60K 15/04

(57) **CLAIM**

The ornamental design for a coolant filler port for a vehicle as shown and described.

DESCRIPTION

FIG. 1 is a top, front perspective view showing my new design;

FIG. 2 is a top, left-side perspective view thereof;

FIG. 3 is a top, rear perspective view thereof;

FIG. 4 is a top, right-side perspective view thereof;

FIG. 5 is a bottom, rear perspective view thereof;

FIG. 6 is a bottom, front perspective view

FIG. 7 is a bottom, right-side perspective view thereof;

FIG. 8 is a bottom, rear perspective view thereof;

FIG. 9 is a bottom, front, right-side perspective view thereof;

FIG. 10 is a left-side view thereof;

FIG. 11 is a right-side view thereof;

FIG. 12 is a front view thereof;

FIG. 13 is a rear view thereof;

FIG. 14 is a top plan view thereof;

FIG. 15 is a bottom plan view thereof;

FIG. 16 is a cross-sectional view taken along line 16-16 of FIG. 9; and,

FIG. 17 is a cross-sectional view taken along line 16-16 of FIG. 12.

The diagonal shaded portions of the cross-sectional views form no part of the claimed design.
